UNITED STATES PATENT OFFICE.

CLARENCE W. CARTER, OF MINNEAPOLIS, MINNESOTA

PROCESS OF LOADING MOLDS WITH MOLDING MATERIAL.

No. 921,082.

Specification of Letters Patent.

Patented May 11, 1909.

Application filed August 9, 1904. Serial No. 220,080.

To all whom it may concern:

Be it known that I, CLARENCE W. CARTER, citizen of the United States, residing at Minneapolis, in the county of Hennepin and State of Minnesota, have invented certain new and useful Improvements in Processes of Loading Molds with Molding Material; and I do hereby declare the following to be a full, clear, and exact description of the invention, 10 such as will enable others skilled in the art to which it appertains to make and use the same.

My invention has for its object to provide an improved process of loading molds with 15 molding material properly compacted for molding, and to the above ends it consists of the novel actions, and manipulations, hereinafter described and defined in the claims.

Figure 1 is a view principally in side elevation, but with some parts sectioned and with some parts broken away, illustrating one form of apparatus by means of which my improved process may be carried into effect; Fig. 2 is a transverse vertical section taken 25 approximately on the line $x^1 x^2$ of Fig. 1.

The numeral 1 indicates the floor of the second story of a building, in which the apparatus is shown as installed.

The numeral 2 indicates a mold which, as 30 shown, is supported by a table 3.

The numeral 4 indicates a supply hopper, which contains the molding material.

The numeral 5 indicates a fan, which, as shown, is supported by brackets 6 in an elevated position. This fan is provided with an air trunk 7 which extends horizontally for some distance, and then is turned vertically downward, and is passed through the floor 1. To the depending end of this trunk 7 is 35 pivoted, or otherwise loosely, attached a tubular discharge nozzle 8, that immediately overlies the mold 2, and terminates some considerable distance above the same.

Working within the supply hopper 4, is a feed screw 9, the shaft of which projects at one end, and is provided with a friction wheel 10. The bearing for the inner end of the screw 9 is cut away at 11, to afford a passage through which the material to be 45 molded may be forced from the hopper, into the air trunk 7, under the action of the screw 9.

Pivoted in bearings 12 on the floor 1, is a bell crank lever 13, the upper arm of which is 50 shown as bifurcated, and the lower arm of which is connected by a link 14 to a long

lever 15, as shown, pivoted to a bearing 16 secured beneath the floor 1. The free end of this lever 15 is connected by a depending link 17 to a foot lever 18 which, as shown, is 55 pivoted to the lower portion of the table 3, in position where it may be readily engaged by the foot of the operator, standing close to the mold 2. In the bifurcated arm of the bell crank 13 is loosely journaled a short 60 shaft 19 which carries a small friction wheel 20 and a pulley 21. A friction wheel 20 is adapted to be pressed into frictional contact with the friction wheel 10 of the feed worm 9, through the lever connections described, 65 by a downward pressure applied to the foot lever 18. A power driven belt 22, shown by dotted lines, runs over the pulley 21 to impart continuous motion to the shaft 19. By varying the pressure on the foot lever 18, 70 frictional contact between the friction wheels 10 and 20 may be varied so as to vary the speed and feeding action of the feed screw 9.

When the fan 5 is set in motion, and the feed screw 9 is driven, the material to be 75 molded will be blown, or shot, as it were, out from the lower end of the nozzle 8 and into the mold 2, under high velocity, and hence will be compacted within the mold by momentum, and without requiring tamping or 80 pressure from any other source. By proper adjustments of the nozzle 8, the material to be molded may be properly distributed within the mold. It will be understood that the 85 material to be molded is relieved from the air pressure before it reaches the mold, and is injected into the mold under the velocity which is acquired while subject to the pressure of the elastic fluid within the air trunk. Hence the air, or other elastic fluid used to 90 95 impel the material to be molded, does not disturb the material which is once delivered into the mold, and has no tendency to blow the same out of the mold.

This process is especially adapted for use 100 in forming concrete building blocks within molds. In the construction of these blocks, the concrete or cement, in plastic condition, is placed within the hopper 4, and is blown, under momentum, or shot into, the mold 2 105 in the manner previously described. With the delivery end of the air trunk turned vertically downward, gravity is caused to assist the pneumatic force in imparting momentum to the molding material which is injected or shot into the mold.

It will, of course, be understood that any

suitable elastic fluid, under pressure, or in other words, that any pneumatic force, may be utilized to impart the required momentum to the molding material. It also, of course, follows that a pneumatic blast, or elastic fluid blast, may be supplied by any suitable device.

The above described process makes it possible to construct concrete building blocks, and other molded objects, with great rapidity and economy.

It is well known that in forming concrete blocks or in compacting other molding material within molds, it is very desirable that such material should be of the same or of some definite density throughout. In the usual attempt to approximate this result, it has been customary to repeatedly place molding material within the mold and repeatedly tamp the same, but this is a slow and consequently an expensive operation, and even when carried out does not accomplish the ideal result. The ideal result is the simultaneous delivery and tamping of the molding material within the mold, under which manipulation the molding material is or may, as is obvious, be evenly compacted throughout the mold. This ideal result I accomplish by my improved process above described. The molding material, by the blast, is delivered with such force that it

is properly tamped in the very act of its delivery.

What I claim and desire to secure by Letters Patent of the United States is as follows:

1. The process of loading molds with molding material, which consists in producing a confined pneumatic blast, in introducing the molding material into the said confined blast, in shooting the said molding material into the mold, under the impelling force of said blast, and in varying the direction of the blast to distribute the said molding material within the mold, whereby the said molding material is tamped simultaneous with its delivery.

2. The process of forming concrete blocks in molds, which consists in producing a confined pneumatic blast, in introducing plastic concrete into the said confined blast, in shooting said plastic concrete into the mold, under the impelling force of said blast, and in varying the direction of the blast to distribute concrete within the mold.

In testimony whereof I affix my signature in presence of two witnesses.

CLARENCE W. CARTER.
